SAFETY FULL ROD COUPLING

Lawrence Jefferson McKinney and Christian
Winther Jensen, Detroit, Mich.

Application June 11, 1936, Serial No. 84,604

8 Claims. (Cl. 74—593)

This invention relates to pumping apparatus of the type employed in connection with oil wells and the like and pertains more particularly to a safety device for interposition between a power mechanism and a pumping apparatus, so that a plurality of pumping devices may be operated by a single power mechanism, in such a manner that a single pumping apparatus may be disconnected from and connected with a power mechanism, with perfect safety during operation of the latter.

The primary object of the present invention is to provide means which may be operated in comparative safety for the purpose of connecting or disconnecting a power driven reciprocating pull rod or the like and a pull rod or member which is connected to a pump. To this end the operation may be accomplished by an operator without handling the power transmitting members, to minimize the probability of an accident.

Another object is to provide a novel safety stop for limiting the amount of movement which can take place by the driven pull rod when a break occurs between the power supply and the pumping device.

A further object is to provide a means for permitting proper adjustment between the power supply source and the pumping apparatus to eliminate frictional losses which would result from misalignment of the power supply and the pumping apparatus as when the power house is upon a hill and the pumping apparatus at a lower elevation. Further, the device provides a means for counteracting thrusts or side motion strains of the power pull rod by adjustable anchor rods between the power house and the safety device, and between the safety device and the terrain on the pump side.

A further object is to provide means of a character referred to above having anchoring means permitting ease of installation, and which facilitates the removal of the device from one location to another.

Other objects will be apparent from the following specification when considered together with the accompanying drawings.

Fig. 1 is a diagrammatic view of an installation which embodies the invention.

Fig. 2 is a detailed view showing mechanism for coupling and uncoupling the power line.

Fig. 3 is a view similar to Fig. 2 showing another position of the parts.

Fig. 4 is a side elevation of one of the coupling elements.

Fig. 5 is a plan view of the coupling element shown in Fig. 4.

Fig. 6 is similar to Fig. 4, but showing the parts in another position.

Fig. 7 is a similar view showing the parts in still another position.

Fig. 8 is a section taken substantially on line 8—8 of Fig. 2.

Fig. 9 is a view similar to Fig. 8 showing the same parts in another position.

Fig. 10 is a plan view of the structure.

Fig. 11 is a sectional view taken on line 11—11 of Fig. 10.

Fig. 12 is a sectional view taken on line 12—12 of Fig. 11.

Fig. 13 is a section taken on line 13—13 of Fig. 10.

Fig. 14 is a diagrammatic perspective of the device.

Fig. 15 is a plan view of the device.

Fig. 16 is a view taken on line 16—16 of Fig. 15.

In Fig. 1 the source of power (not shown) transmits power by the drive means 2 to the power dispenser 3, which in revolving transmits the imparted energy to a common revolving eccentric 4, to which may be joined a number of reciprocable power lines or pull rods, such as shown at 5, for hooking on to a number of pumping devices all of which is common practice in the oil industry.

The rod 5, for delivering the said power in substantially a straight line motion, has an eye 1 formed on the end thereof detachably receiving a hook 7. The hook 7 is pivotally connected at 8 to the carrying members 9, as best shown in Fig. 4, which carry a control member 10 slidably supported by the guide member 11 which is attached to the coupling members by the fastening means 12. The member 10 has a stop at each end, as at 13 and 13a, adapted to engage the ends of the guide member 11 to restrict sliding movement thereof.

As shown in Fig. 2, a movable blocking plate 16 has a slot 17 formed in one end, the plate being mounted to slide in the track pieces 18 secured to the adjustable height legs 19, which have right angle bends at the bottom to form supporting feet. On the face of the slide member 16 and pivotally attached at 20 thereto is a release member 14 having an inclined or cam face 48. A link 24 is pivotally and slidably mounted on plate 16 as at 25. This link is pivotally connected to a control lever 29 as at 27, 55

which lever is in turn pivotally mounted on the frame at 38.

Referring to Fig. 10, the V-bent anchoring rod 34, threaded at both ends, is adjustably joined to the loop members 35 that are welded to the track members 18. Pivotally connected at the mid-point of the anchor member 34 by a loop formed on one end of the rod is a rod member 36 having a threaded portion on the opposite end and adjustably fastened to the cross member 37, positioned near the base of the device. From the apex of the tripod thus formed, and connected to the apex by an eye piece formed on one end, is the anchoring member 38, the free end of which extends preferably back to the power source to be anchored in the concrete base of the power house. On the pumping apparatus side of the device is secured a second V-bent anchoring member 39 having two threaded ends, one end being adjustably fastened to the same cross member 37 at its mid-point, the other end being operably connected to a second cross member 40. At the mid-point of the V-bent member 39 is a pivotally connected anchor rod 41 having its free end anchored in the ground.

Referring again to Figs. 10, 11 and 12, will be seen a power pull rod guide support and safety stop member 42. The said plate is supported by the threaded members 43 through integral brackets 44, and a cross member 40, to track members 18, as shown in Fig. 13. An opening 45 located in the side of the plate 42 and a slot 47 provides access to a bearing member 46 positioned substantially near the center of the plate 42 for "threading" the power pull rod through the plate.

In installation the coupling 9 is joined with the power line or rod 5a, and the hook 7 to the coupling eye 1 on the powered pull-rod 5, at a point in the power line about 20 feet from the power house. The frame and blocking apparatus is then placed adjacent to said cooperating coupling members 9 and 1, as in Fig. 15, such that the blocking plate 16 is at about the mid-point of reciprocation of the power line, as in Fig. 16. The adjustable length legs 19 of the frame will take care of any height connection from the power take-off. The adjustment of the guy rods 34, 36 and 39 guying the frame of the terrain allowing adjustment of the vertical axis of the frame to set the frame perpendicular to the line of travel of the power line, and the horizontal axis normal to the line of travel of the power line, when the conditions of installation require placing the apparatus upon a hill, in a depression, or upon an incline. Similarly the plate 42 may be adjusted by loosening the nut members on each side of the plate and moving the plate to fit the angle of reciprocation of the power line.

In operation, when it is desired to uncouple the powered pull rod 5 from the coupling member 9 to "hang-up" the pumping apparatus, the operator grasps the control lever 29 and moves it in a counter-clockwise direction, as viewed in Fig. 2, sliding the blocking plate 16 and attached parts to the position as viewed in Fig. 3, at a time when the coupling 9 is in the right hand position 9a, as viewed in Fig. 16. The power line will continue to move forward in normal travel until the coupling member 9 butts against the blocking plate, that has been moved across the line of travel of the power pull rod 5, as in Fig. 6. As the coupling 9 approaches the blocking plate, the control member 10 and stop 13 forces the pivot member 14 to the left as viewed in Figs. 4 and 6, against the blocking plate 16, collapsing the spring 50 in its

socket 49 as in Figs. 8 and 9. The arcuate shape of the right hand side of the pivot member 14 as viewed in Fig. 2 or 3 is to allow for a certain amount of circular movement of the pull rod 5 in normal reciprocation and still provide positive contact for the control member 10. The purpose of the spring 50 is to hold the pivot member 14 away from the blocking plate 16 in normal operation as in Fig. 8. The normal position of the pivot member renders the link member 24 inoperative after the finger 21 formed on the end of member 24, contacts the upper side of the pivot member 14. If the spring 50 was not in the apparatus the pivot member 14 might be locked in the out position before the tension was removed from the power line, and the control member 10 on butting against the pivot member 14 would bend it and cause serious damage to the link 24 and control lever 29. After the control member 10 has collapsed the pivot member, and the tension in the power line is relieved by the coupling 9 abutting the blocking plate, the link 24 is free to be moved clockwise as viewed in Fig. 2 to engage the inclined plane or cam face 48 of the pivot 14. By further counter-clockwise movement of the control lever 29, the pivot member 14 is moved clockwise as in Fig. 9, moving the control member 10 from the left to right engaging the nose 15 by the stop 13a and forcing the hook 7 up out of union with the power line, as viewed in Fig. 7. The hook is now held in this suspended position by locking the control lever in the in position by a pin through the hole 33 of the T-arm member 32. If the operator inadvertently attempts to actuate the control lever when the coupling is in some other position than that stated, the cross-dimensions of the slot, being smaller than the hook 7, will not engage the hook 7 to be rendered operative as a blocking member.

To couple the eye 1 of the powered rod 5 with the hook 7, the operator merely waits until the coupling eye 1 is in the position of furthest forward travel and is just beginning the reciprocation from left to right as viewed in Fig. 16. The control lever is then moved clockwise as viewed in Fig. 2, the link 24 and finger 21, in turn being moved away from the cam face 48, and the hook 7 moving clockwise, as viewed in Fig. 7, through the action of gravity. The member 14 is now free to be pivoted towards the plate member 16 collapsing the weak spring 50. The power will then pull the cooperating coupling members away from the plate 16, the spring 50 will expand to its normal length, and the blocking member may be returned to its normal position through further clockwise movement of the control lever as viewed in Fig. 2, allowing the power line to reciprocate in normal operation. Due to the shape of the hook 7 the eye 1 will form an operative coupling therewith only when moving in a direction from left to right as viewed in Fig. 16. Further the operator is prevented from removing the plate 16 from a blocking position when the power line is uncoupled by the inherent weight of the pumping apparatus. Again, even if the operator should succeed in moving the plate from a blocking position, the coupling would only move a distance from the blocking plate to the safety stop plate 42 when it would be restrained there, as in Fig. 16.

In the foregoing description and following claims, the term "power line" is used to define the combined and connected reciprocating rods or cables 5 and 5a, along with the necessary couplings connecting the same. In other words,

it is the line between the pump and the power source.

We claim:

1. A coupling structure for use in a reciprocating power line located between a power source and the pump of an oil well or the like comprising, cooperating coupling members in the line arranged to be connected and disconnected, abutment means on the line positioned on the side 5 of the coupling members nearest the pump, a stationary frame, a blocking member mounted in said frame and arranged to be shifted into the path of the abutment for taking the load of the pump and relieving the tension on the coupling members, means for shifting the blocking member into blocking position, means for actuating one of the coupling members when the tension is relieved for shifting one of said coupling members out of coupling relation with the other coupling member, and means for blocking said actuating means from uncoupling said members when the latter are under tension.

2. A coupling structure for use in a reciprocating power line for the pump of an oil well or the like comprising, cooperating coupling members in the line between a power source and pumping apparatus arranged to be connected and disconnected, abutment means on the line on the side of the coupling members nearest the pumping apparatus, a stationary frame, a blocking member 25 slidable in said frame arranged to be shifted into the path of the abutment for taking the load of the pumping apparatus and relieving the tension on the coupling members, a manually operated lever and intermediate slotted linkage connected thereto to permit lost motion with respect to said lever and for shifting the blocking member into blocking position, and a pivoted cooperating member arranged to 30 be shifted by said manually operated lever and adapted to actuate one of the coupling members when the tension is relieved for shifting one of said coupling members out of coupling relation with the other coupling member, said slotted linkage and lost motion between said linkage and 35 said lever permitting release and control of one of said coupling members when said coupling member is brought into coupling relation with the other coupling member prior to the shifting of said blocking member from blocking position.

3. A coupling structure for use in a reciprocating power line for the pump of an oil well or the like comprising, cooperating coupling members in the line between a power source and a pumping apparatus arranged to be connected and disconnected, abutment means on the line on the side of the coupling members nearest the pumping apparatus, a frame with slide members placed adjacent to said abutment means, a blocking plate slidable in said frame arranged 40 to be moved into the path of the abutment for taking the load of the pumping apparatus and relieving the tension on the coupling members, manually operable means for shifting the blocking plate into blocking position, and means operably connected to said manually operable means for actuating one of the coupling members when the tension is relieved for shifting one of said coupling members out of coupling relation with the other coupling member.

4. A coupling structure for use in a reciprocating power line for the pump of an oil well or the like comprising, cooperating coupling members in the line between a power source and a pumping apparatus arranged to be connected and

disconnected, abutment means on the line on the side of the coupling member nearest the pumping apparatus, a stationary frame, a blocking member slidable in said frame and arranged to be shifted into the path of the abutment for taking the load of the pumping apparatus and relieving the tension on the coupling members, means for shifting the blocking member into blocking position, means for actuating one of the coupling members when the tension is relieved for shifting one of said coupling members out of coupling relation with the other coupling member whereby the shifting operation of the blocking member is accomplished in two steps, first to a blocking position, an interruption until the said tension is relieved and the second step of shifting one of the coupling members out of coupling relation with the other coupling member, and means for blocking said actuating means to prevent the shifting of one of the coupling members from coupling relation until said tension is relieved.

5. A coupling structure for use in a reciprocating power line for the pump of an oil well or the like comprising, cooperating coupling members in the line arranged to be connected and disconnected, abutment means on the line, a stationary frame, a blocking member in said frame arranged to be shifted into the path of the abutment for taking the load of the pumping apparatus and relieving the tension on the coupling members, a manually operated lever and intermediate slotted linkage for shifting the blocking member into blocking position, and a pivoted cooperating member for actuating one of the coupling members when the tension is relieved for shifting one of said coupling members out of coupling relation with the other coupling member, the pivoted cooperation member having an arcuate shape of that portion engaging one of the coupling members to provide positive contact with said member in event of a circular movement during the reciprocation of the power line.

6. In a mechanism of the type described, safety coupling means in a reciprocating power line comprising a hook member and an eye member, an abutment on the hook side of said line, the said hook being pivoted to said abutment, a stationary supporting device, a manually operable blocking means movable in said supporting device into the path of said abutment for taking the load on the hook side of the line and relieving the tension on the coupling members, means manually operable, only when said tension is relieved, to pivot the hook from its position of engagement with the eye member, and a guide member for the line on the hook side of the coupling rigidly fastened to and spaced from the supporting device and adapted to serve as a guide for the reciprocating line and as a safety stop for said abutment.

7. In a mechanism of the type described, safety coupling means in a reciprocating power line comprising a hook member and an eye member, an abutment on the hook side of said line, the said hook being pivoted to said abutment, a stationary supporting device, a manually operable blocking means movable in said supporting device into the path of said abutment for taking the load on the hook side of the line and relieving the tension on the coupling members, means manually operable, only when said tension is relieved, to pivot the hook from its position of engagement with the eye member, and an adjustable plate member, having an opening therein,

- rigidly fastened to and spaced from the supporting device and adapted to have the reciprocating line on the hook side of the coupling threaded through the opening in said plate member, said opening being smaller than the axial cross-section of said abutment whereby the plate member will serve as a guide for the line and as a safety stop for said abutment.
8. A safety coupling structure for use in a reciprocating power line comprising, cooperating coupling members in the line, a stationary frame, blocking means in said frame adapted to block the reciprocal movement of one of said coupling

members, a cam member adapted to operatively engage one of said coupling members, and manually operable means operably connected with said blocking means and said cam member and movable to one position to shift said blocking means to blocking position and thereby remove the strain from the coupling members, and movable to a second position to actuate said cam member to shift one of the coupling members out of coupling relation with the other coupling member.
